UNITED STATES PATENT OFFICE.

ROBERT BURTON ELLIOTT, OF SUGARRIDGE, OHIO.

COMBINED WAGON BOX AND RACK.

SPECIFICATION forming part of Letters Patent No. 681,204, dated August 27, 1901.

Application filed September 24, 1900. Serial No. 30,953. (No model.)

To all whom it may concern:

Be it known that I, ROBERT BURTON ELLIOTT, a citizen of the United States, residing at Sugarridge, in the county of Wood and State of Ohio, have invented a new and useful Improvement in a Combined Wagon Box and Rack, of which the following is a specification.

My invention relates to improvements in wagon-bodies; and the main object of my invention is the provision of a body which may be employed as a grain-box or a hay or straw rack, a novel construction of joints being provided to support the sides when extended.

I have illustrated my invention in the accompanying drawings, in which—

Figure 1 is a perspective view of my invention used as a grain-box or wagon-body. Fig. 2 is a similar view with the sides swung open as when used as a stock-rack or hay-rack. Fig. 3 is a bottom perspective, and Fig. 4 is a detail view, of the bottom and sides, showing the construction of the joint at the junction of the standards and the bed's cross-pieces.

Similar letters refer to similar parts throughout the several views.

The bed A of the wagon is provided with the sides B, front end-gate C, and rear end-gate D. The sides operate as folding leaves and are connected to the body by hinges a. They are normally held in position by means of the iron plates or flanges b, attached by means of bolts to the standards c, which project below the sides and are mitered upon their inner sides. Secured to the under side of the bed and in line with the standards c are the cross-pieces d, which have their outer ends mitered, so as to fit flush with the mitered ends of the standards c when the sides are extended, the plate b being adapted when the sides are extended to contact the under side of the cross-pieces d and steady the joint. The wooden pieces or braces h are secured to the bed upon the under side and run length-

wise thereof, being adapted to rest upon the 45 bolster of a running-gear and give the body an even support throughout its length. I secure a cross-piece i upon the pieces h, so that the wagon-body may be more readily held in place.

The front end-gate is rigidly secured to the bed, while the rear end-gate is swingingly secured by means of hinges to the top part of the frame K, which is rigidly secured to the bed, the gate being adapted to be swung 55 outward when the body is in use as a grain-box or stock-rack.

I employ a rod e with eyes and hooks, so that the sides may be extended and be additionally supported by connecting these rods 60 to the gates and sides.

From this description it is evident that I provide a wagon-body which may be converted into a grain-box, a hay-rack, or a stock-rack, as the sides may be closed when the 65 body is used as a grain-box or wagon-body and be swung open either upon one or both sides to form a stock or hay rack, as desired.

I claim—

In the herein-described wagon-body, a bed, 70 a series of cross-pieces secured upon the under side thereof and having mitered ends, sides hinged to said bed and adapted to swing outwardly, standards secured to the sides having mitered lower ends to contact the 75 mitered outer ends of the cross-pieces when the sides are extended, and flanges or braces carried by the said lower ends of the standards adapted to contact the lower sides of the cross-pieces when the sides are extended. 80

In testimony whereof I have signed my name to this specification in the presence of two subscribing witnesses.

ROBERT BURTON ELLIOTT.

Witnesses:

ROY KINTNER,
ROBERT P. CAMPBELL.
